RAILWAY SWITCH OPERATING MECHANISM

Herbert L. Bone, Forest Hills, and Kenneth J. J. McGowan, Swissvale, Pa., assignors to The Union Switch & Signal Company, Swissvale, Pa., a corporation of Pennsylvania

Application October 20, 1937, Serial No. 170,060

6 Claims. (Cl. 246—411)

Our invention relates to railway switch operating mechanisms, and particularly to improvements in mechanisms of the type shown and described in Letters Patent of the United States No.

5 1,654,023, granted to C. C. Thorn for Switch throwing and locking mechanism, on December 27, 1927.

One object of our invention is to provide a mechanism of the type described which is capable 10 of operating the heavier and therefore stiffer switches now being employed, and which has a high overall efficiency.

Another object of our invention is to provide a mechanism of the type described which is economical to build and maintain.

A further object of our invention is to provide a mechanism of the type described which readily adapts itself to use with either a right-hand or a left-hand switch layout regardless of 20 whether the point adjacent the mechanism is normally closed or normally open.

A still further object of our invention is to provide a novel circuit controller for detecting the position of the switch points.

25 Other objects and characteristic features of our invention will appear as the description proceeds.

We shall describe two forms of railway switch operating mechanisms embodying our invention, 30 and shall then point out the novel features thereof in claims.

In the accompanying drawings, Fig. 1 is a view showing a railway switch operated by a switch operating mechanism embodying our invention. 35 Fig. 2 is an enlarged top plan view of the switch operating mechanism shown in Fig. 1, the cover of the mechanism being removed and some of the parts being shown in section to better illustrate the construction of the remaining parts.

40 Fig. 3 is a vertical longitudinal sectional view of the mechanism shown in Fig. 2 taken substantially on the line III—III of Fig. 2. Fig. 4 is a sectional view taken substantially on the line IV—IV of Fig. 3. Figs. 5, 6, and 7 are detail views 45 of various parts of the mechanism shown in the preceding views. Figs. 8 and 9 are detail views showing modifications of a portion of the mechanism shown in the preceding views. Figs. 10 and 11 are diagrammatic views showing the application 50 of a switch operating mechanism embodying our invention to a single switch leading to a siding which is provided with a derail. Figs. 12 and 13 are diagrammatic views showing a crossover layout wherein a certain sequence of operation of the two ends is enforced by means of

switch operating mechanisms embodying our invention. Figs. 14, 15, and 16 are diagrammatic views showing another crossover layout provided with switch operating mechanisms embodying our invention.

5 Similar reference characters refer to similar parts in each of the several views.

Referring first to Fig. 1, the reference character A designates a railway switch comprising, as usual, two fixed rails 1 and 1a and two movable rails or switch points 2 and 2a. The fixed rails 1 and 1a are laid on tie plates 3, and are secured to crossties 4 in the customary manner. The movable rails 2 and 2a are fastened together by a front rod 5 and a head rod 6, and may be moved into a normal or a reverse position by means of a throw rod 7 which is connected with the head rod 6 through the medium of a switch basket 8. When the switch occupies its normal position, in which position it is shown in the drawings, the movable 20 rail 2 engages the fixed rail 1, and the movable rail 2a is spaced from the fixed rail 1a. When the switch is reversed, however, the movable rail 2a then engages the fixed rail 1a, and the movable rail 2 is spaced from the fixed rail 1.

25 Secured to an elongated pair of the ties 4 adjacent the outer side of the rail 1 is a switch operating mechanism B embodying our invention, which mechanism we shall now describe. As best seen in Figs. 2, 3, and 4, the mechanism B, 30

in the form here shown, comprises a suitable casing 10 which encloses the operating parts of the mechanism, and which is closed at its upper end by a removable cover 11. The cover 11 is held in place at its right-hand end by means of a U-bolt 12 which overlies fingers 14 cast on the cover, and at its left-hand end by an adjustable hasp 18. The U-bolt 12 is secured to lugs 13 cast on the sides of the casing 10, by means of nuts 15 disposed above the lugs, and other nuts 16 40 disposed below the lugs, the lower nuts being made square, and being seated in a recess formed by depending projections 13a provided on the lugs, whereby it is impossible to remove the nuts 16 without first removing the cover, and then back- 45 ing off the upper nuts 15 a sufficient amount.

The adjustable hasp 18 comprises a strap 18a pivotally attached by means of a pin 18b to a nut 18c screwed onto the upper end of a T-headed bolt 19d. The bolt 19d extends downwardly 50 through a hole in a lug 19 provided on the cover, and cooperates at its head with a pair of fingers 20 formed on the left-hand end wall of the casing 10. The strap 18a slips over a hasp eye 21 secured to the cover 11, thereby permitting the parts to be 55

locked in place by a padlock or the like. To fasten the cover in place the fingers 14 are first inserted under the U-bolt 12, and the head of the bolt 18d is then placed under the fingers 20. The nut 18c is next tightened by using the strap 18a as a means for turning the nut, after which the strap is dropped over the eye 21 and a padlock is inserted through the eye. To remove the cover, the opposite procedure is followed. It will be obvious, of course, that when the cover is unfastened, it can be readily lifted clear of the casing, thus permitting ready access to the operating parts of the mechanism. To insure a good seal between the cover and the casing, the cover is formed with a peripheral groove containing packing 23 which seals against the casing.

Located within the casing 10 of the mechanism B is a motion plate 25 (see Fig. 5) which is guided to slide longitudinally in a direction parallel to the track by means of guide rollers 26 and 27 secured to the underside of the motion plate adjacent its opposite ends and cooperating with guideways 28 provided on the bottom wall of the casing. The motion plate 25 has rack teeth 29 formed in its upper surface on one side of the center line, the spaces between the teeth being disposed below the adjacent upper surface of the plate, and being curved inwardly at their ends for a purpose which will be made clear presently. The rack teeth 29 mesh with a segment gear 30 mounted on a square shaft 31, which shaft, in turn, is mounted at its ends in bearing sleeves 32 and 33 journaled in bosses 34 and 35 formed in the side walls of the casing 10. The bearing sleeve 32 is provided at its outer end with a flange 32a, and is secured to the shaft 31 by means of a through bolt 36. The bearing sleeve 33 is also provided at its outer end with a flange 33a, and secured to the shaft 31 adjacent the flange 33a by means of a through bolt 37. A hand-throw lever 38 which serves as a means for reciprocating the motion plate 25 between its two extreme positions. The segment gear 30 is slidably mounted on the shaft 31 with enough clearance so that it can be readily slipped off the shaft, and has its teeth curved at their ends in a manner similar to the ends of the spaces between the rack teeth, whereby the segment gear is maintained in the proper longitudinal position on the shaft to mesh with the rack teeth by the cam action which results between the curved ends of the teeth on the gear and the curved ends of the spaces between the rack teeth, thus eliminating the necessity for any means for securing the segment gear to the shaft. One advantage of this construction is that the shaft can be turned end for end to permit the mechanism to be mounted on the opposite side of the switch from that shown without unfastening any of the parts from the shaft but the bearing sleeve 32.

A roller 40 is secured to the underside of the motion plate 25 adjacent one side thereof at a point equally spaced from the rollers 26 and 27, and this latter roller cooperates with cam faces 41 and 42 formed on an escapement crank 43 (see Fig. 2). The escapement crank 43 is formed integrally with the upper end of a switch actuating shaft 44, the shank of which is provided with two bearing surfaces 45 and 46 separated by a squared portion 47. The bearing surfaces 45 and 46 are journaled in vertically aligned bearings 48 and 49 formed respectively in the bottom of the casing 10, and in a depending stirrup 50 which is provided on the underside of the casing, and secured to the square portion 47 of the shaft

is a removable switch operating arm 50a which is pivotally attached to the free end of the throw rod 7.

A lock bar 51 extends longitudinally of the casing 10 directly above the motion plate 25, and is slidably mounted adjacent one end in a guide plate 52 bolted to the end wall of the casing in a position to close an opening 53 through which the slide bar extends with considerable clearance. The other end of the lock bar is slidably mounted in a guideway 54 (see Figs. 3 and 4) formed in a frame 55 which is bolted to the casing 10 adjacent its left-hand end by means of four bolts 56, and which serves as a support for a circuit controller, as will appear hereinafter. The lock bar is operatively connected with the motion plate by means of a stud 57 secured to the lock bar and extending into a transversely extending slot 58 formed in the upper side of the motion plate. The parts are so proportioned that when the guide plate 52 is secured to the casing 10, the stud 57 will be held in operative engagement with the slot 58, but that, when the guide plate 52 is unbolted from the casing, the stud can be lifted clear of the slot 58 and the lock bar can be removed from the casing through the opening 53.

The left-hand end of the lock bar 51 cooperates with a notch 59 provided in a lock rod L which is secured to the front rod 5. The parts are so proportioned that the notch 59 will align with the lock bar when and only when the switch occupies its full normal position, and that, when the notch 59 is in alignment with the lock bar, and the motion plate is in its left-hand extreme position, the lock bar will have entered the notch 59, as shown in Fig. 3, and will thus have locked the switch in its normal position.

The operation, as a whole, of the portion of the apparatus thus far described is as follows: When the hand-throw lever 38 is rotated to its normal extreme position in which it is shown in the drawing, the motion plate 25 is moved to its extreme left-hand or normal position in which it is shown in Figs. 2 and 3, and under these conditions, the switch points are held in their normal positions by engagement of the roller 40 with the cam surface 41 of the escapement crank 43. Furthermore, under these conditions, the lock bar 51 enters the notch 59 in the lock rod L, thus locking the switch points in their normal positions.

When it is desired to reverse the switch, the hand-throw lever 38 is rotated in a counterclockwise direction through an angle of substantially 180° from the extreme position shown to its opposite or reverse extreme position. This rotation of the hand-throw lever acts through the segment gear 30 and rack teeth 29 to move the motion plate to its right-hand extreme position, and as the motion plate moves to this latter position, the first part of the movement withdraws the lock bar 51 from the notch 59 in the lock rod L to unlock the switch, the intermediate part of the movement causes the roller 40 to engage the cam surface 42 of the escapement crank 43 and rotate the escapement crank to the position in which the straight portion of the cam surface 42 extends parallel to the track, thereby rotating the switch actuating shaft to its reverse extreme position, and hence moving the switch points to their reverse extreme positions, while the final part of the movement of the motion plate causes the roller 40 to move along the straight portion of the cam surface 42 to such a position that any

tendency of the switch actuating shaft to rotate in a direction to permit the switch points to move away from their reverse positions is effectively blocked by the roller. It will be seen, therefore, that when the switch points occupy their reverse extreme positions, they are effectively held in these positions due to the coaction between the roller and the escapement crank, and it will also be seen that any force which may be exerted on the switch tending to restore it to its normal position will cause a transverse force to be exerted on the motion plate rather than a longitudinal force, thus avoiding any tendency to reverse the hand-throw lever due to any force which may be exerted on the switch.

When the switch has been moved to its reverse position, and it is desired to restore it to its normal position, the hand-throw lever 38 is returned to the position shown. The operation of the parts under these conditions is exactly the reverse of that just described, and this operation will be apparent from the foregoing description and from an inspection of the drawings without further detailed description.

25 A bearing plate 60 is bolted to the upper side of the casing 10 adjacent its right-hand end, and journaled in a vertical bearing 61 formed in this bearing plate is a target staff 62, the lower end of which carries a crank 63. The crank 63 is provided with a depending pin or cam follower 64 which extends into, and cooperates with, a cam slot 65 formed in the upper face of the motion plate 25, whereby movement of the motion plate between its two extreme positions will rotate the target staff through an angle of 90°. The upper end of the target staff is intended to be provided with suitable signaling means here shown as the usual target 62c (see Fig. 1), and in order to permit the target to be turned to the desired position with respect to the track, the lower end of the staff 62 and the hub of the target crank 63 are provided with matching serrations, whereby by changing the relative position of the serrations on the staff and on the crank 45 different positions of the shaft with respect to the motion plate for any given position of the motion plate can be obtained. The crank is secured to the target staff by means of a clamping bolt 66 which extends through aligned holes 50 formed in split portions of the hub of the crank and engages a groove 62a formed in the lower end of the target staff. The target staff is maintained in the proper vertical position by the hub of the crank and by a shoulder 62b which is 55 formed on the staff, and which cooperates with the upper end of the bearing 61 in the bearing plate 60.

Under certain conditions which will be made clear hereinafter, the motion plate is turned end for end, and in order to permit the target staff to be operated under these conditions, the motion plate is provided in its upper side with another cam slot 65a which is similar to, but oppositely disposed from, the cam slot 65.

65 In the event that it is not desired to provide the mechanism with a target, the opening in the casing 10 which is closed by the bearing plate 60 when the target is provided may then be closed by a blank plate bolted to the casing 70 in the same manner that the bearing plate is bolted to the casing.

The mechanism may also include a suitable circuit controller for controlling signals for governing the movement of traffic over the switch. As 75 shown in the drawings, this circuit controller

comprises a rocker arm 70 (see Figs. 2, 3 and 7) pivotally supported intermediate its ends on a pin 71 secured within a pair of spaced upstanding lugs 72 provided on the frame 55. The rocker arm 70 is disposed directly above the lock bar 51, and is provided with a cam face 70a which cooperates with a cam face 73a provided on a cam dog 73 secured to the upper side of the lock bar 51 in such manner that when the lock bar is moved to the position in which it is withdrawn from the notch 59 in the lock rod L the cam face 73a will engage the cam face 70a shortly before the lock bar has cleared the notch and will positively rotate the rocker arm in a counterclockwise direction, as viewed in Fig. 3, from its normal extreme position to a reverse extreme position. The rocker arm is also provided with a cam face 70b which joins the right-hand end of the cam face 70a, and which cooperates with the top of the lock dog to maintain the rocker arm 20 in its reverse extreme position whenever the switch is unlocked.

A contact operating member 75 (see Fig. 4) is pivotally attached to the left-hand end of the rocker arm 70, and is guided to move vertically by means of upwardly extending studs 76 which are provided on the frame 55, and which pass freely through clearance holes 77 formed in the operating member. Surrounding the studs 76 between the frame and the contact operating member are compressed coil springs 78, whereby the operating member is biased to an upper position in which it engages adjustable stop nuts 79 screwed onto the upper ends of the studs, it being noted that since the contact operating member is pivotally attached to the rocker arm 70, the springs 78 also serve to bias the rocker arm to its normal position in which it is shown in Fig. 3. Two superposed insulating blocks 80 and 81 are secured to the upper side of the operating member, and extending between these blocks are the free ends of a plurality of flexible contact fingers 82, here shown as four in number. Each contact finger 82 cooperates with a fixed contact member 83 to form a contact 82-83. 45 Each contact finger 82 and the associated contact member 83 are clamped to the opposite sides of an insulating block 84 by means of terminal posts 85 and 86, and the insulating block 84, in turn, is supported on lugs 87 projecting upwardly from the frame 55. Each terminal post 85 is electrically connected with the associated contact finger 82, but is insulated from the associated contact member 83, as will be apparent from an inspection of the drawings; while each terminal post 86 is electrically connected with the associated contact member 83, but is insulated from the associated contact finger 82. The parts are so proportioned that when the rocker arm 70 occupies its normal extreme position in which it is shown in the drawings, each contact 82-83 will be open, but that, when the rocker arm is rotated to its other extreme position, each contact 82-83 will then be closed. It will be apparent, therefore, that the contacts 82-83 65 will become closed whenever the lock bar is withdrawn from the notch 59 in the lock rod L to unlock the switch.

It should be pointed out that the contact finger 82 and contact member 83 which comprise each contact may, if desired, be reversed to provide a normally closed instead of a normally open contact.

It should also be pointed out that by adjusting the stop nuts 79 the positions to which the 75

contact operating member 75 and rocker arm 70 are biased can be varied, thus eliminating any necessity for individual contact adjustment and also permitting adjustment to be made for slight 5 manufacturing variations.

The circuit controller also comprises a point detector lever 90 (see Figs. 4 and 6) which is pivotally supported on a pin 91 mounted in the frame 55, and which is biased, by means of a 10 spring 92 interposed between the frame and a laterally projecting latch arm 93 the function of which will be made clear presently, in a counterclockwise direction to the position in which a roller 94 mounted in a depending lug 95 formed 15 on the point detector lever enters a notch 96 in a point detector rod D. The point detector rod D is slidably mounted in the casing 10, and as shown in Fig. 1 is attached, by means of a link 97 and a bolt 98 to the movable rail 2 of the 20 switch A in the usual and well-known manner. The point detector lever 90 is also provided with a laterally projecting arm 99 having a rounded end 100 which overlies and cooperates with the conical head 101a of a finger 101 which is ad- 25 justably mounted in an upstanding lug 10c provided on the rocker arm 70. The notch 96 in the point detector rod D is so disposed and the parts are so proportioned that the roller 94 will enter the notch 96 when and only when the 30 movable rails 2 and 2a of the switch A occupy their normal extreme positions and the movable rail 2 is in proper engagement with the fixed rail 1. The parts are further so proportioned that when the roller 94 is within the notch 96 and the 35 rocker arm 70 occupies its normal position, the rounded end 100 of the point detector lever will just touch the upper side of the conical head 101a of the finger 101, but that, when the roller 94 is forced out of the notch 96, the resultant 40 clockwise rotation of the point detector lever will cause the rounded end 100 of the point detector lever to cooperate with the head 101a of the finger 101 in a manner to rotate the rocker arm 70 to its reverse extreme position, thus caus- 45 ing the contacts 82-83 to become closed. It follows, therefore, that any displacement of the switch point 2 away from the rail 1 when the parts are in the positions shown in the drawings 50 will operate the contacts 82-83.

50 It should be noted that the depending lug 95 which supports the roller 94 is disposed adjacent one end of the point detector lever 90, and that the point detector lever is provided at its opposite end with a similar depending lug 102 (see Fig. 4) to which the roller 94 can be attached in the event that it is desired to have the switch point 1 normally closed instead of the switch point 2.

As is well understood, the contacts of a circuit controller of the type described are utilized 60 to control signals governing traffic over the associated switch, and their primary purpose is to cause the signals to indicate "stop" unless the switch points occupy their proper positions relative to the fixed rails and are properly locked in these positions. With the portion of the circuit controller thus far described, these contacts will adequately do this in all instances where the apparatus is in proper working order. However, 65 if a train improperly trails the switch while it is locked in its normal position in the manner shown, a dangerous condition might possibly exist because, under these conditions, while the switch points will be displaced at the top an 70 amount which would easily operate the point 75

detector contacts of the circuit controller if the detector rod could be connected with the points at the top of the points, it is necessary for clearance reasons to connect the detector rod to the switch points some distance below the top of the 5 points, where, due to the rolling of the points during the trailing, the amount of the movement may not be more than one-half of that occurring at the top of the points, and, furthermore, after a train has trailed the switch, the points will 10 usually spring back toward their original positions a certain amount. As a result, the final displacement of the point detector rod may be very little, if any, more than the displacement which would correspond to a maximum permiss- 15 ible opening of the closed switch point, which is the setting at which the point detector contacts become opened, while the opening of the closed point at the top may be sufficient to be extremely dangerous for subsequent high speed 20 train movements. In order to insure that this dangerous condition will be detected, we provide latching mechanism so constructed that if a train trails the switch while it is locked, this 25 latching mechanism will retain the circuit controller contacts in their closed positions until after they are subsequently released by a maintainer. Thus, even though the switch points spring back toward their proper positions after the train has trailed through the switch, the sig- 30 nals governing traffic over the switch will continue to display a restrictive indication until the maintainer releases the contacts of the circuit controller and permits them to return to their 35 normal positions. It is assumed that before the maintainer does this, he will inspect the switch points, and, if damaged, repair them, thus guarding against a dangerous condition due to damaged 40 switch points.

Referring now again to Figs. 2, 3, and 4, the 40 latch mechanism just referred to comprises the previously referred to latch arm 93, the free end of which is provided with a latch dog 93a which cooperates with a latch catch 105 having a screw-threaded upper portion 105a which is adjustably 45 screwed through a tapped hole provided in a latching member 106 (see Fig. 3). The latch catch is also provided with a rectangular latch head 105b having its opposite sides cut away to form two notches 105c and 105d, and the latch 50 catch is adapted to be locked, by means of a lock washer 107, and a jam nut 108 provided on the threaded portion 105a above the latching member 106, in an adjusted position in which either the side of the latch head 105b containing the 55 notch 105c, or the opposite side, faces the latch dog. To facilitate adjusting the latching member, the upper end of the threaded portion 105a is provided with one or more saw kerfs for the 60 reception of a screw driver.

The latching member 106 extends transversely 65 of the casing 10 directly above the intermediate portion of the rocker arm 70, and is pivotally supported at its ends on a rod 110 mounted in upstanding lugs 111 provided on the frame 55. 70 A curved cam arm 112 extends toward the right from the latch member 106 and is provided adjacent its right-hand end with a cam face 112a which cooperates, under certain conditions to be described presently, with the cam dog 73 carried by the lock bar 51. The latching member 106 is constantly biased to rotate in a clockwise direction by means of the cam arm, and also by means of a spring 113 which is stretched between a laterally projecting lug 114 provided on the 75

frame and a spring arm 115 provided on the latching member.

The parts of the latching mechanism are so proportioned and the latch catch 105 is so adjusted that when the roller 94 on the point detector lever 90 is within the notch 96 in the point detector rod D, and the lock bar 51 occupies its locking position in which its left-hand end is within the notch 59 in the lock rod L, as shown in the drawings, the latch head 105b of the latch catch 105 will engage the end of the latch dog 93a on the point detector lever 90 just above the notch 105c, and will thus prevent the latching member from rotating in a clockwise direction past the position in which it is shown in the drawings. It should be pointed out that the spring 113 materially aids in preventing vibration, and consequently, wear, between the latch catch and the latching dog when the parts are in the positions shown since the latch catch is normally held firmly against the end of the latching dog.

Bolted to the bottom wall of the casing 10 at the left-hand end of the casing directly above an opening 119 is an insulating terminal board 120 provided with clamping means 121 for gripping double bond wires as well as with terminal screws for the reception of conductors 122 by means of which the bond wire clamping means 30 may be electrically connected with the terminal posts 86. Holes 123 are also provided in the terminal board 120 to enable line wires to be led directly to the terminal posts.

In explaining the operation of the circuit controller as a whole, we shall first assume that the parts are in their normal positions in which they are shown in the drawings, and that the switch is moved to its reverse position by means of the hand-throw lever 38 in the manner previously described. Under these conditions, the movement of the lock bar 51 which takes place before the lock bar becomes completely withdrawn from the notch 59 in the lock rod L will cause the cam face 73a of the cam dog 73 to engage the cam face 112a of the cam arm 112 and rotate the latch member 106 in a counterclockwise direction, as viewed in Fig. 3, to a position in which the latch catch 105 is out of engagement with the latch dog 93a on latch arm 93, and will also cause the cam face 73a to engage the cam face 70a on the rocker arm 70 and rotate the rocker arm from its normal extreme position to its reverse extreme position, thereby closing the contacts 82-83. The motion of the rocker arm 70 also lowers the finger 101 to such a position that when the switch points subsequently start to move and force the roller 94 out of the notch 96 in the lock rod, the point detector lever will be free to rotate without causing the rounded end 100 of the arm 99 of the point detector lever to engage the finger 101. The motion of the lock bar which takes place after the roller 94 has been forced out of the notch 96 in the lock rod will cause the dog 73 to move past the cam face 112a on the cam arm 112, and will thus permit the latching member 106 to rotate in a clockwise direction, as viewed in Fig. 3, to the position in which the cam arm 112 on the latching member engages the top of the lugs 72 which support the pin 71, but the dog 73 will continue to engage the rocker arm 70 during the balance of the movement of the lock bar and will thus retain the rocker arm in its reverse extreme position.

When the switch points have been moved to 75 their reverse positions, and the hand-throw lever

38 is operated to restore them to their normal positions, the operation of the circuit controller will be substantially the reverse of that just described, it being noted that under these conditions, the latching member will be rotated to the position in which the latch catch 105 is clear of the latch dog 93a by engagement of a cam face 73c provided on the cam dog 73 with the cam surface 112a on the latch arm 112, and will subsequently be retained in this position until after 10 the notch 96 in the point detector rod D moves into alignment with the roller 94 by engagement of the top of the dog with the cam surface 112a. Inasmuch as the operation of the circuit controller during movement of the switch points to 15 their normal positions is substantially the reverse of that which takes place during movement of the switch points to their reverse positions by the hand-throw lever, it is believed that this operation will be understood from an inspection of the 20 drawings and from the foregoing description without further detailed description.

We shall now assume that the parts are in the positions in which they are shown in the drawings and that a train trails the switch. Under 25 these conditions, the extreme forces which are exerted on the switch points by the trailing train will force the point detector rod D upwardly, as viewed in Fig. 2, far enough to cause the roller 94 on the point detector lever 90 to move out of 30 the notch 96 in the point detector rod, and will thus cause the point detector lever to rotate in a clockwise direction as viewed in Fig. 3. This clockwise rotation of the point detector lever will act through the arm 99 and finger 101 to rotate 35 the rocker arm 70 in a counterclockwise direction to its reverse extreme position, thus closing the contacts 82-83. This rotation of the point detector lever will also cause the latch arm 93 to move downwardly to the position in which 40 the lock dog 93a aligns with the notch 105c in the latch catch 105. The latch member 106 will therefore now rotate, due to its bias, to the position in which the latch dog 93a enters the notch 105c in the latch catch 105. It will be apparent from an inspection of the drawings that when the latch dog 93a has once entered the notch 105c, the point detector lever will be held in the position in which the roller 94 is out of the notch 96, and the rocker arm 50 70 will therefore be held in the position in which the contacts 82-83 are closed, until the latch catch is subsequently moved out of engagement with the latch dog even if the point detector rod subsequently returns to the position in which the notch 96 aligns with the roller 94. It follows that in order to release the contact operating member and permit the contacts 82-83 to become opened after they have once been closed in the manner just described, it is 55 necessary to restore the latching member 106 to its normal position in which it is shown in the drawings. This may be done either by removing the cover 11 and raising the cam arm 112 manually, or by throwing the switch movement by 60 hand to its reverse position, in which latter case cam dog 73 will raise the cam arm 112 and will thus release the latch catch. When the point detector contacts are unlatched by operating the mechanism to its reverse position by hand, if the 65 switch points have been disturbed at all by the trailing train, the roller 94 on the point detector lever will not reenter the notch 96 in the lock rod when the switch is subsequently restored to 70 its normal position, because the displacement of 75

the switch points will cause the lock rod to be out of adjustment, and as a result the plunger lock contacts will remain open, thus insuring that an indication of the damaged condition of the switch 5 will be given.

An important feature of a switch operating mechanism embodying our invention is that by properly assembling the parts, the same parts may be used for either a left-hand or a right-hand switch layout regardless of whether the switch point adjacent the mechanism is normally closed or normally open. For example, the layout shown in Fig. 1 is a right-hand layout with the switch point adjacent the switch operating 10 mechanism normally closed. If, now, with this layout, it is desired to have the switch point adjacent the mechanism normally open instead of normally closed, this result may readily be accomplished by turning the motion plate 25 end 15 for end, rotating the target staff in a counterclockwise direction to the position in which the pin 57 on the target crank 63 enters the cam slot 65a in the motion plate, removing the switch operating arm 50a from the switch actuating 20 shaft 44 and rotating the switch actuating shaft in a clockwise direction, as viewed in Fig. 1, through an angle of approximately 120° to the position in which the escapement crank is disposed at the opposite side of the mechanism, 25 and then reassembling the operating arm on the switch actuating shaft in a position displaced 60° in a counterclockwise direction from the position shown in the drawings, and finally removing the roller 94 from the lug 95 on the point detector 30 lever and attaching it to the lug 102.

For a left-hand layout, that is to say for a layout in which the switch operating mechanism is mounted on the left-hand side of the track when facing the switch points, if it is 35 desired to have the switch point adjacent the mechanism normally open, the mechanism will be assembled in the manner shown in Figs. 2, 3, and 4 except for the fact that the shaft 31 will be turned end for end to cause the hand-throw 40 lever 38 to be disposed at the outer side of the mechanism.

For a left-hand layout with the point adjacent the mechanism normally closed, the mechanism will be assembled in the manner described above 45 for a right-hand layout with the point adjacent the mechanism normally open, except for the fact that the shaft 31 will be turned end for end to cause the hand-throw lever to be disposed at the outer side of the mechanism.

50 A mechanism embodying our invention may be used to operate both a single switch and a derail by merely connecting the pipe line which operates the derail with the lock bar 51 in the manner shown diagrammatically in Figs. 10 and 11.

Under some conditions of operation, it is desirable to enforce a certain sequence of operation between two mechanisms embodying our invention which mechanisms are used to operate 55 two switches at the opposite ends of a crossover between the main track and a siding. When this is the case, it is necessary to replace the lock bar shown in Figs. 2 and 3 with what is commonly referred to as a loose lock bar. Such a lock 60 bar is shown in Figs. 8 and 9 from which it will be noted that this latter lock bar, which is designated by the reference character 115, is not provided with any driving stud, but is provided with an upstanding dog 115a and with a recess 115b 65 adjacent the left-hand end of the dog 115a. The

dog 115a and recess 115b are adapted to cooperate with a projecting arcuate lug 30a which is provided on the segment gear 30, to prevent movement of the segment gear except when the lock bar is moved to the right to a position in 5 which the switch is unlocked, and in order to cause the segment gear to properly cooperate with the loose lock bar, it is necessary to reverse the position of the segment gear 30 with respect to the shaft 31 in the manner shown in Figs. 8 10 and 9. When the segment gear is assembled in this manner, the lug 30a extends over the lock bar 115 and cooperates with the recess 115b and dog 115a in such manner that when the switch is locked by means of the lock bar, the lug 30a 15 will engage the top of the dog and prevent operation of the hand-throw lever away from its normal position, but that, when the switch is unlocked, the lug will enter the recess 115b, and will permit operation of the hand-throw lever. 20

A layout using a pair of mechanisms, one of which employs a loose type of lock bar, for operating the two switches at the ends of a crossover between a main track and a siding is shown diagrammatically in Figs. 12 and 13, and a layout employing two mechanisms both equipped with loose lock bars for operating the two switches at the ends of a crossover between two main tracks is shown diagrammatically in Figs. 14, 15, and 16. It will be noted that in the layout shown in Figs. 14, 15, and 16, the lock bars 115 of the mechanisms which operate the switches are independently operated from a separate stand located intermediate the two movements. 35

It should be pointed out that the segment gear 30 is so constructed that when the motion plate driven type of lock bar is used, it will be impossible to operate the movement unless the hub of the segment gear 30 is placed over the lock bar, 40 as shown in Fig. 2, whereas, when the loose type of lock bar is used, it will be impossible to operate the movement unless the segment gear is assembled in the opposite manner as shown in Figs. 8 and 9. This construction insures that the 45 mechanism will always be assembled in the proper manner.

Although we have herein shown and described only two forms of railway switch operating mechanisms embodying our invention, it is understood that various changes and modifications may be made therein within the scope of the appended claims without departing from the 50 spirit and scope of our invention.

Having thus described our invention, what we 55 claim is:

1. A switch operating mechanism comprising a casing, a motion plate, means for mounting said motion plate in said casing for movement longitudinally of the casing in such manner that 60 said motion plate can be turned end for end, means for reciprocating said motion plate, means driven by the motion plate for operating a switch, a transverse slot in each end of said motion plate, a lock rod extending into said casing and movable with the switch, a lock bar slidably mounted in said casing in removable guides and cooperating at one end with said lock rod, and a stud on said lock bar adapted to enter one or the other of said slots in said motion plate to provide a driving connection between said motion plate and said lock bar, the parts being so proportioned that said stud will be held in operative engagement with one or the other of said slots when said guides are in place. 65 70 75

2. In combination, a railway switch, a lock rod connected with the switch points to move therewith and provided with a notch, a lock bar, means for at times moving said lock bar into the notch in said lock rod to lock the switch points in one extreme position and for at other times withdrawing said lock bar from said notch to unlock the switch points, a contact, means for operating said contact whenever said lock bar is withdrawn from said notch, a point detector rod connected with the switch, means operated by said detector rod for operating said contact if the switch points are displaced from said one position while they are locked and for latching said contact in its operated position, and means effective if said lock bar is withdrawn from the notch in said lock rod when said contact is latched in its operated position for unlatching said contact.
3. In combination, a switch, a lock rod connected to the switch to move therewith, a lock bar movable between a locking and an unlocking position and effective when in its locking position for engaging said lock rod to lock said switch in one extreme position, means for moving said lock bar, a contact operating member biased to one position, a rocker arm connected at one end with said contact operating member, means carried by said lock bar and cooperating with said rocker arm for moving said contact operating member from its one position to its other position whenever said lock bar is moved to its unlocking position, a point detector rod secured to the switch and provided with a notch, a pivoted point detector lever provided with a roller and biased to a position in which said roller enters said notch, means on said point detector lever engaging means carried by said rocker arm for actuating said rocker arm to move said contact operating member from its one position to its other position whenever said roller is forced out of said notch; and a contact controlled by said contact operating member.
4. In combination, a switch, a lock rod connected to the switch to move therewith, a lock bar movable between a locking and an unlocking position and effective when in its locking position for engaging said lock rod to lock said switch in one extreme position, means for moving said lock bar, a contact operating member biased to one position, a rocker arm connected at one end with said contact operating member, means carried by said lock bar and cooperating with said rocker arm for moving said contact operating member from its one position to its other position whenever said roller is forced out of said notch; and a contact controlled by said contact operating member.
5. A switch operating mechanism comprising a casing, a motion plate, means for mounting said motion plate in said casing for movement longitudinally of the casing in such manner that said motion plate can be turned end for end, means for reciprocating said motion plate, means driven by the motion plate for operating a switch, a cam slot formed in each end of said motion plate, a target staff mounted in said casing, and means on said target staff adapted to enter one or the other of said cam slots to provide a driving connection between said motion plate and said target staff in either position of the motion plate.
6. A switch operating mechanism comprising a casing, a motion plate, means for mounting said motion plate in said casing for movement longitudinally of the casing in such manner that said motion plate can be turned end for end, means for reciprocating said motion plate, means driven by the motion plate for operating a switch, a cam slot formed in each end of said motion plate, a target staff mounted in said casing, and a crank secured to said target staff and adjustable to different angular positions with respect to said staff and cooperating with one or the other of said cam slots to provide a driving connection between said motion plate and said target staff in either position of the motion plate.
